UNITED STATES PATENT OFFICE.

GEORGE L. WITSIL, OF PHILADELPHIA, PA., ASSIGNOR TO HIMSELF,
CHARLES M. RHODES, AND C. W. OLDENBERG, OF SAME PLACE.

IMPROVEMENT IN PETROLEUM-STOVES.

Specification forming part of Letters Patent No. 42,059, dated March 22, 1864.

To all whom it may concern:

Be it known that I, G. L. WITSIL, of Philadelphia, Pennsylvania, have invented a Stove in which to Burn Oily Hydrocarbons; and I do hereby declare the following to be a full, clear, and exact description of the same, reference being had to the accompanying drawings, and to the letters of reference marked thereon.

My invention relates to the use of coal-oil or other oily hydrocarbons for generating heat in stoves; and it consists of a receptacle or vessel for containing ashes or equivalent powder mixed with oil, the vessel being covered or partly covered with a dome to which air is admitted from below, and the dome having an opening, above which is a disk, the whole being arranged within a stove, as described hereinafter.

In order to enable others to make and use my invention, I will now proceed to describe its construction and operation.

On reference to the accompanying drawings, which form a part of this specification, Figure 1 is a vertical section of my improved stove for burning oily hydrocarbons; Fig. 2, a sectional plan, and Fig. 3 a top view of the dome detached from the stove.

Similar letters refer to similar parts throughout the several views.

A represents the base-plate of the stove; B, the sheet-iron cylinder; F, a sliding door; G, the oven, and H the outlet pipe, communicating with an adjacent chimney.

On the base-plate A and within the cylinder B rests the receptacle C and deflector D, the receptacle consisting of a dish for the reception of ashes mixed with coal-oil or other oily hydrocarbon, and the deflector consisting of a hollow dome placed over the dish and having at the top an opening, a, a disk, D', on the end of a rod, b, attached to the bottom of the receptacle C, being so situated in respect to this opening that between the edge of the latter and that of the disk there shall be an annular space through which the flame passes.

A number of openings, arranged in the manner illustrated in Fig. 2, are made in the base-plate A, beneath and in contact with which a plate, E, with similar openings, is hung to a central pin, i, so that by turning the plate more or less air may be admitted to the space within the dome D. The surface

of the saturated ashes having been ignited, and the dome having been placed in its proper position concentric with the receptacle C, the flame will be directed toward the annular space between the disk D' and the edge of the opening a of the dome, to which space the air admitted to the interior of the dome is directed and brought into intimate contact with the flame, which above the dome and disk is clear and brilliant and capable of imparting the desired heat to the stove and to the oven G. The oil will continue to rise to the heated surface of the mass of ashes until the whole of the oil is consumed, there being no necessity for any stirring or agitation of the mixture. When the oil has been entirely consumed, the sliding door F may be elevated, the dome withdrawn, the receptacle removed, and a new supply of oil mixed with the ashes.

I prefer, however, to make use of several receptacles containing the mixture of coal-oil and ashes, so that one may always be at hand for ready insertion into the stove when required.

Pulverized bricks and other powdered substances not readily acted on by the heat may be used in place of ashes. I prefer the latter, however, as they have been found to be most efficient in practice.

The coal-oil usually employed for illuminating purposes may be used or even crude petroleum or any of the oily hydrocarbons.

Without confining myself to the particular form of the deflector D, disk D', and receptacle C, which may be modified to suit stoves of different characters without departing from the main features of my invention, I claim and desire to secure by Letters Patent—

1. The combination of the disk C, base-plate A, its openings h, and plate E or its equivalent.
2. The combination of the dish C, dome D, and disk D', constructed and arranged within a stove or heater, substantially as and for the purpose herein set forth.

In testimony whereof I have signed my name to this specification in the presence of two subscribing witnesses.

GEO. L. WITSIL.
